US0D1043128S

(12) **United States Design Patent** (10) **Patent No.:** **US D1,043,128 S**
(45) **Date of Patent:** **** Sep. 24, 2024**

(54) **TOOTHBRUSH HEAD**

(71) Applicant: **The Gillette Company LLC**, Boston, MA (US)

(72) Inventors: **Uwe Jungnickel**, Königstein (DE); **Dominik Langhammer**, Frankfurt (DE)

(73) Assignee: **The Gillette Company LLC**, Boston, MA (US)

(**) Term: **15 Years**

(21) Appl. No.: **29/862,858**

(22) Filed: **Dec. 13, 2022**

Related U.S. Application Data

(60) Continuation of application No. 29/841,827, filed on Jun. 8, 2022, now Pat. No. Des. 976,010, which is a division of application No. 29/762,793, filed on Dec. 18, 2020, now Pat. No. Des. 957,135.

CLAIM

The ornamental design for a toothbrush head, as shown and described.

DESCRIPTION

FIG. 1 is a perspective view of a toothbrush head;

FIG. 2 is a front view thereof;

FIG. 3 is a left-side view thereof;

FIG. 4 is a rear view thereof;

FIG. 5 is a right-side view thereof;

FIG. 6 is a top view thereof; and,

FIG. 7 is a bottom view thereof.

Broken lines in the drawings depict portions of a toothbrush head that form no part of the claimed design.

1 Claim, 2 Drawing Sheets
